United States Patent Office

Des. 229,564

Patented Dec. 11, 1973

229,564

COMBINED DATA ENTRY AND DISTRIBUTION TERMINAL

George E. Chadima, Jr., 3624 Skylark Lane SE.,
Cedar Rapids, Iowa 52403

Filed Feb. 4, 1971, Ser. No. 112,836

Term of patent 14 years

Int. Cl. D14—02

U.S. Cl. D26—5 C

FIG. 1 is a top plan view of a combined data entry and distribution terminal showing my new design.

FIG. 2 is a left side elevational view thereof, the right side being identical thereto;

FIG. 3 is a front elevational view thereof, the back being plain and unornamented;

FIG. 4 is a front perspective view thereof.

I claim:

The ornamental design for a combined data entry and distribution terminal, substantially as shown and described.
